UNITED STATES PATENT OFFICE.

JOSEPH G. SALTZMAN, OF BROOKLYN, NEW YORK, ASSIGNOR TO ACOUSTI-SCOPE CORPORATION, A CORPORATION OF NEW YORK.

MOTION-PICTURE AND SOUND-REPRODUCING APPARATUS.

1,341,933.

Specification of Letters Patent.

Patented June 1, 1920.

Application filed March 15, 1915, Serial No. 14,339. Renewed October 3, 1919. Serial No. 328,316.

To all whom it may concern:

Be it known that I, JOSEPH G. SALTZMAN, a citizen of the United States, residing in the borough of Brooklyn, in the county of Kings, city and State of New York, have invented new and useful Improvements in Motion-Picture and Sound-Reproducing Apparatus, of which the following is a specification.

10 This invention relates to a combined machine for taking or projecting photographs or pictures in successive sequence and a sound reproducing machine or phonograph, and it is the primary object of the invention to provide a combined apparatus of this character in which the driving means are common to both and means are provided to retard or advance the movement of one machine relative to the movement of 15 the other to maintain a picture being projected in synchronism with the record being reproduced.

20 A further object of the invention is to provide in apparatus of this character a sound reproducing machine having a plurality of record carriers either one or more of which are adapted to be automatically placed into operative connection with the driving means at a predetermined time.

25 30 Another object of the invention is to provide a quick releasable connection or coupling between the motion picture machine and the driving means.

35 Other objects and advantages will hereinafter appear.

In the drawings accompanying and forming a part of this specification, Figure 1 is a front elevation, partly in section, of an apparatus showing an embodiment of my 40 invention, only a portion of the motion picture machine being shown in dotted lines.

Fig. 2 is a side elevation partly broken away.

45 Fig. 3 is a perspective view of the upper portion of the sound reproducing apparatus, the cover being broken away to show the interior or driving mechanism.

50 Fig. 4 is a plan view of a detail showing the manner of connecting a record carrier to the driving means.

Fig. 5 is a front elevation of the mechanism shown in Fig. 4.

55 Fig. 6 is a sectional side elevation illustrating the means to automatically throw a

record carrier into operative connection with the driving means at a predetermined time.

Fig. 7 is a sectional detail showing the manner of operatively connecting and actuating the means to throw a record carrier into engagement with the driving means.

Fig. 8 is a sectional detail of the quick releasable coupling to connect the motion 65 picture machine with the driving means.

Fig. 9 is a perspective detail view showing the manner of releasing the latch mechanism to release a record carrier and permit it to be operatively connected to the 70 driving means.

Fig. 10 is a detail perspective view of the means to release a record carrier to cause it to be automatically placed in operative connection with the driving means.

Fig. 11 is a detail view in perspective of the means to connect a record carrier to the driving means; and

Fig. 12 is a detail perspective view of a portion of the main driving shaft showing 80 the means to retard or increase the speed of one portion of said shaft relative to the other portion.

Similar characters of reference designate like parts throughout the different views of 85 the drawings.

The embodiment of my invention illustrated in the drawings comprises a suitable supporting frame consisting of connected posts or standards 14 supporting a 90 table 15 adjacent their upper ends upon which the operating mechanism for the record carriers and the picture machine are mounted, this mechanism being inclosed by a removable cover, as shown at 16.

95 As stated an object of the invention is to provide a sound reproducing machine having a plurality of record carriers, in the present instance shown as two in number, whereby as the successive phases of a scene 100 in a play and the performers are being photographed a record is simultaneously made of the spoken parts or conversation, or to record a song being sung and simultaneously photograph the different phases of the singer in successive sequence; or to project such pictures in successive sequence and simultaneously therewith in proper synchronization reproduce the talking parts of the play or the song. This is not possible without in- 110

terruption with the use of commercial phonographic records since they do not have the capacity. I therefore, provide a sound reproducing machine having a plurality of 5 record carriers the driving means being common to both the carriers and the picture machine, and the carriers being so arranged that one or more may be in operative connection with the driving means while the others 10 are inoperative, and provide means to throw either of said record carriers into operative connection with the driving means at a pre-determined time or times, thus producing an apparatus in which there is no interruption 15 of the operation of the picture machine, and the records can be changed while the apparatus is in operation.

The picture machine and the sound reproducing machine are operated from a main 20 driving shaft 17 driven from the source of power, such as a motor M, by suitable power transmission mechanism, in the present instance consisting of a friction driving wheel 18 fixed to the shaft of the motor co-operating 25 with a friction disk 19 mounted on a shaft 20 to rotate therewith and have sliding movement thereon, the disk being maintained in yielding engagement with the wheel 18 by springs 21 coiled about pins 23 30 fixed at one end in the disk and confined between said disk and a collar 22 fixed to the shaft 20 in which the pins slidably engage and serve to connect the friction disk to said shaft. The upper end of the shaft 20 is 35 journaled in the table 15 and is geared, as at 24, to a shaft 25 which is geared, as at 26, to the shaft 17, and geared, as at 27, to a shaft 28, the gearing 24, 26 and 27 preferably being spiral gearing.

40 In the present instance I have shown the records R as being of the disk form and as two being utilized, said disk being adapted to be carried by rotatable tables or carriers comprising heads 29 fixed to vertical spindles 32 supporting disks 30 operatively connected thereto by a suitable friction gripping material 31, such as rubber, interposed therebetween, the ends of the spindles projecting through the heads and disks and 45 having a rubber gasket or sleeve 33 thereon to assist to frictionally carry the disks by the heads. The records are carried on the disks 30 and connected thereto by a pin engaging in an opening in the records. To the 50 lower ends of the spindles 32 are fixed worm wheels 34 with which the worms 35 loose on the shaft 28 mesh, the worms being connected to one member of clutches 36 also loose on the shaft 28, with the co-operating 55 clutch members 37 mounted on the shaft to rotate therewith and have sliding movement thereon, the spindles being coupled to the shaft 28 through said clutches.

The main driving shaft 17 also operates 60 the picture machine which may be of any

suitable construction and is represented in dotted lines in Fig. 1 at P. The main driving shaft consists of a pair of axial sections, the one section 17 driving the record carriers and the other section 17' driving the picture 70 machine. These sections are connected in axial alinement by differential gearing (Figs. 1 and 12), comprising a bevel gear 38 loose on the shaft 17 and a pair of bevel pinions 39, 39, rotating on an axis transverse to 75 the axis of the shaft 17 meshing with said gear and carried by a block fixed to the end of and rotatable with the shaft 17, said pinions also meshing with a bevel gear 40 fixed to the end of shaft section 17'. It will be 80 obvious that as the shaft section 17 rotates it will carry the pinions 39 with it and said pinions will carry the gear 40 with them, the other gear 38 being held stationary for a 85 purpose to be hereinafter described; this latter gear being stationary the pinions 39 will travel around the same causing the shaft section 17' to rotate faster or slower according to the ratio of the gearing than the shaft section 17, the gearing in the present instance being such that the shaft section 17' 90 will rotate at twice the speed of the shaft section 17.

In this type of apparatus the great difficulty has been to make the picture machine 95 and sound reproducing machine synchronize due to the creeping of the film as the picture is being projected, or due to a portion of the film being damaged with the necessity of removing such portion of the 100 film. To cause the two machines to synchronize without the necessity of stopping the apparatus I provide means to retard or increase the speed of one of the shaft sections, in the present instance shown as the shaft 105 section 17' connected to the picture machine. To retard or increase the speed of said shaft section while in operation relative to the shaft section 17 there is connected to the gear 38 and loose on the shaft 17 a worm 110 wheel 41, a worm 42 fixed to a rotatable shaft 43 meshing with said worm wheel, the latter shaft being normally stationary preventing rotation of the worm wheel and its connected gear 38. On the end of the shaft 115 43 projecting out from the cover 16 is a crank 44 whereby the shaft 35 may be manually rotated in either direction. Should it be desired to retard the speed of the shaft section 17' the shaft 43 is rotated in one 120 direction thereby rotating the gear 38 and the pinions 39 and gear 40 connected to the shaft section 17', and by rotating the shaft 43 in a reverse direction the speed of the shaft 17' is increased.

As stated either one or both of the record carriers may be in operative connection with the driving shaft 17 and as the operation of one of the records is terminated means are provided to automatically connect the other 130

record carrier to the driving shaft. For this purpose each of the clutches has a pivoted shifter 45, springs 46 normally tending to maintain the clutch members in operative engagement. To maintain the clutches out of operative engagement I provide a pivoted latch 46' in the form of a rocker having a notch adjacent each end in which a projection 47 on the shifters are adapted to engage, as shown in Fig. 3. In Fig. 3 the record carrier at the right is in operative connection with the driving shaft while the opposite carrier is inoperative, the clutch being disconnected and maintained in such position by the engagement of the shifter extension 47 in a latch notch.

To release the clutch at a predetermined time to connect its coöperating record carrier to the driving shaft, I provide tripper mechanism to release the latch 46', consisting of a pair of rockers 48, 49 extending across the framework and pivotally supported at their ends. In the present instance these rockers are in the form of three parallel bars connected to constitute an angular construction, as shown in Figs. 2, 4, 5 and 6. Each of these rockers has a cam member 50 fixed thereto which engages with one arm of pivoted levers 51, (Figs. 4 to 6 and 9) when the rockers are rocked, depressing said end of the levers and raising the opposite ends which engage with the ends of angular extensions 52 of the latch 46 passing through the table 15 and raising the ends of the latches thereby throwing them out of operative engagement with the shifter extensions 47 and permitting the springs 46' to pull and maintain the clutches in operative connection. The rockers are actuated by a pair of trippers comprising arms 53, 54 pivotally carried by a support 55 slidably mounted on rods 56' and 57' extending transversely of the machine to permit the arms to have movement transversely of the machine. These arms at their upper ends have pivoted spring influenced hooked pawls 56, 57 (Figs. 2 and 6) normally bearing against the rockers and when the arms are moved in one direction passing over the rockers with the hooked portion engaging in back of the same and when the arms move in reverse direction actuating the rockers. The arms are normally maintained in the position shown in Figs. 2 and 6 by a spring or springs 58.

To actuate the arms I provide a rotatable drum 59 having a spiral groove 60 in the periphery extending from end to end and in which engages a spring detent or plunger 61 carried by the arm support 55. As the drum rotates by the engagement of the plunger 61 in the drum groove the arms will move to the right of Fig. 1, and should it be desired to move the arms in a reverse direction the arm support is released from the drum by

withdrawing the detent 61 from the drum groove by the knob 62 when the arm support may be moved back at will.

To actuate the arms at a predetermined time and thereby connect the record carrier 70 or carriers to the driving shaft 17 the drum is provided with removable or adjustable pins 63, 64, the pins 63 being longer and of less diameter than the pins 64. The pins 64 as the drum rotates are adapted to engage 75 with a forked extension 65 of the arm 54 thereby rocking said arm against the tension of its spring causing the dog 57 to ride under the rocker 48, and as the pin 64 rides off of the arm extension 65, the spring 58 80 will pull back the arm 54, the dog 57 actuating the rocker 48 lifting the right hand end of the latch 46 and operatively connect the record carrier 32 at the right to the driving shaft.

The arm 53 will be actuated when a pin 63 which will pass between the fork of the extension 65 engages an extension 66 of the other arm 53 rocking said arm in a similar manner to the rocking of the arm 54, the 90 dog 56 actuating the rocker 49 raising the opposite end of the latch 46 and connecting the record carrier at the left to the driving shaft. It will be obvious that when one of the record carriers is in operating position 95 the other carrier is manually disconnected and locked in such position by causing the shifter extension 47 to engage with a latch notch, when a record on such carrier may be removed and another substituted without 100 stopping the apparatus and without interfering with the operation of the apparatus whatever.

The drum is provided with equally spaced apart graduations extending around the 105 periphery thereof, the space between each graduation representing a certain length of film fed during the projection or taking of a picture. The drum is also provided with openings at these graduated points for the 110 engagement of the pins 63, 64, and the drum being rotated at a speed relative to the speed of the projecting machine that the location of the pins can be readily located to operate the means to connect the record carriers to 115 the driving shaft and can be readily predetermined.

To retard and stop the rotation of a record carrier when it is disconnected from the driving means by the throwing of a clutch 120 out of engagement by its shifter, the shifters have an extension 67 to engage with a member 68 to cause the latter to frictionally engage with the worm wheel 34 of a carrier.

The drum is also driven from the shaft 125 17 by a shaft 69 (Fig. 7) geared to the shaft 17, as at 70, and having a worm 71 to rotate therewith and have sliding movement thereon, said worm meshing with a worm wheel 72 which is releasably connected to 130

the drum by a spring detent 73 carried by said wheel engaging in an opening in a head of the drum. By the release of said pin the drum may be rotated at will independent of 5 its operating means.

To permit of adjustment of the drum so that the movement thereof will correspond and be in proper timed relation to the record carriers, the shaft 69 is so mounted that the 10 worm 71 can be lifted out of mesh with the worm wheel 72. For this purpose one end of the shaft is journaled in a bearing 74 slidably mounted in a bracket 75, a spring 76 normally maintaining said bearing and 15 the shaft in its uppermost position. After the drum has been adjusted relative to the record carriers, which must of necessity in some instances be a very fine adjustment should the worm 71 rest upon a tooth of its 20 coöperating worm wheel by turning a thumb nut 77 in either direction the worm may be adjusted along its shaft until it engages in a tooth space of its coöperating worm wheel.

To permit of the quick release of the projecting machine from the sound reproducing machine, or the substitution of a camera for such projecting machine, the shaft section 17' consists of two sections 17' and 17" and are connected by a quick releasable coupling. This coupling consists of cutting away a portion of each shaft section at the end for substantially one half of its diameter so that the ends of the shaft sections have a mating connection, as clearly shown 35 in Fig. 8. The shaft section 17" slidably carries a sleeve 78 having two internal diameters, the end of the sleeve of greater diameter being on the section 17" which has a collar upon which the sleeve directly 40 engages thereby leaving a space between the shaft and sleeve in which is located a spring 79 coiled about the shaft and confined between the collar and a shoulder formed by the end of the sleeve of reduced diameter, 45 the said latter end of the shaft bearing directly upon the mating ends of the shaft sections. It will be readily understood that by shifting the sleeve against the tension of the spring and away from the mating shaft 50 ends the shaft can be readily uncoupled.

In the commercial type of camera for taking photographs of successive phases of an object or objects the operating shaft to actuate the mechanism to feed the film intermittently and to expose portions of the film during the periods of rest is rotated at one half the speed of the operating shaft of a commercial projecting machine to actuate the mechanism to project the pictures of such film, and to compensate for this when utilizing the sound reproducing apparatus with a camera, the shafts 17 and 25 are provided with a pair of supplemental gears 80 and 81 to be substituted for the gears 83 and 85 84 of the gearing 24, 26, these gears being

so mounted on their respective shafts that they may be readily substituted one for the other.

By constructing the turn tables or carriers for the records as shown, the disk 31 may be 70 adjusted at will on the head 29 so that the starting portion of the record may be placed in proper starting position with relation to the transmitter or sound reproducer T so that when a record carrier is placed in operative connection with the driving shaft 17 by its clutch it will at once reproduce the matter on the record. The engagement of the pin 33' in the opening of the record positively connects the record to the table. 80

The drum 55 is mounted in the framework to be readily removable. For this purpose the ends of the drum have a pivot recess in which engage supporting pivots, the pivot for one end of the drum being carried by a 85 bracket 85 fixed to a platform 86 supported by the standards 14, the pivot for the other end of the drum being carried by a bar 87 hingedly supported at one end by the framework, as at 88, the other end being releasably supported, as at 89, to prevent accidental releasing of the same. 90

The speed of the driving shaft 17 is regulated through the friction transmitting mechanism 18, 19. For this purpose the 95 motor to which the driving wheel 18 is connected is mounted on a table 90 supported by the standards to have sliding movement in an axial direction between a pair of gibs 91 toward and away from the axis of rotation of the disk 19. (Figs. 1 and 2.) To adjust the motor and maintain it in its adjusted position there is connected to one end of the motor a screw threaded stem 92 supported in a screw threaded opening in a 100 bracket 93 mounted on the table 90, the threaded stem having a hand wheel connected thereto to facilitate the rotation thereof. It will be obvious that by rotating the hand wheel in one direction the motor 110 with the wheel 18 will be moved toward the shaft 20 and as it is rotated in a reverse direction it will be adjusted laterally of the disk 19.

Variations may be resorted to within the 115 scope of my invention, and portions of the invention may be used without others.

Having thus described my invention, I claim:

1. The combination with a machine having a drive shaft for projecting pictures in successive sequence and a sound reproducing machine having a drive shaft, of means to couple the drive shafts of said machines together and operative to synchronize a picture being projected with the record reproduced by the sound reproducing machine, comprising a gear fixed to the driving shaft of one of said machines, pinions revoluble with the driving shaft of the other machine 120 125 130

and in mesh with the gear to couple the shafts together and normally revolve the two shafts at the same speed, manually operative means to rotate said pinions independent of their movement with the shaft to retard or increase the speed of the one shaft relative to the other, and a source of power connected to one of said machines.

2. The combination with a machine having a drive shaft for projecting pictures in successive sequence and a sound reproducing machine having a drive shaft, of means to couple the shafts of said machines together and operative to synchronize a picture being projected with the record reproduced by the sound reproducing machine, comprising a gear loose on the driving shaft for the sound reproducing machine, a pair of pinions revolvable with said shaft and in mesh with the gear thereon, said pinions being adapted to be rotated on an axis transverse to the axis of rotation of the shaft, a gear fixed to the driving shaft of the projecting machine to mesh with the pinions to couple the two shafts together and normally revolve the two shafts at the same speed, and means to rotate the gear loose on the shaft of the sound reproducing machine to rotate said gear in the same direction as said shaft or in reverse direction to retard or increase the speed of the driving shaft of the picture machine.

3. The combination with a machine having a drive shaft for projecting pictures in successive sequence and a sound reproducing machine having a drive shaft, of means to couple said machines together and operative to synchronize a picture being projected with the record reproduced by the sound reproducing machine, comprising a gear loose on the driving shaft for the sound reproducing machine, a pair of pinions revolvable with said shaft and in mesh with the gear thereon, said pinions being adapted to be rotated on an axis transverse to the axis of rotation of the shaft, a gear fixed to the driving shaft of the projecting machine to mesh with the pinions to couple the two shafts together and normally drive them positively at the same speed, a worm wheel fixed to the loose gear, a worm in mesh with said worm wheel and normally holding said gear against movement, and a manually operative crank connected to the worm and operative to rotate the worm and connected gear and thereby the pinions in either direction at will to retard or increase the speed of the shaft of the picture projecting machine for the purpose specified.

4. In apparatus of the class specified, the combination of a machine to take or project pictures in successive sequence; a sound reproducing machine having a pair of record carriers; means to simultaneously drive the both machines; a clutch for each of the

record carriers to operatively connect them to the driving means; means to normally maintain one of the clutches in inoperative position and its coöperating record carrier inoperative; a shifter for each clutch; a latch to coöperate with either one of said shifters to maintain its connected clutch in inoperative position; and means to actuate said latch at a predetermined time to cause either of the clutches to be thrown into operative position and connect its coöperating record carrier to the driving means, comprising a tripper, and means to actuate said tripper.

5. In apparatus of the class specified, the combination of a machine to take or project pictures in successive sequence; a sound reproducing machine having a pair of record carriers; means to simultaneously drive the both machines; a clutch for each of the record carriers to operatively connect them to the driving means; means to normally maintain one of the clutches in inoperative position and its coöperating record carrier inoperative; a shifter for each clutch; a latch to coöperate with either one of said shifters to maintain its connected clutch in inoperative position; a tripper to actuate the latch; and a rotatable drum having lateral projecting pins to actuate the trippers.

6. In sound reproducing apparatus, the combination of a pair of record carriers; a shaft to drive both of said carriers; a clutch for each carrier to operatively connect the carriers to the shaft or disconnect them therefrom; a shifter for each clutch; and a latch coöperating with said shifters to normally maintain one of the clutches in operative engagement to connect one of the carriers to the driving shaft and the other clutch in inoperative position; a tripper for said latch to release either one of said clutches to operatively connect its coöperating record carrier to the shaft; and a rotatable drum having laterally projecting pins to actuate said tripper.

7. In sound reproducing apparatus, the combination of a pair of record carriers; a shaft to drive both of said carriers; a clutch for each carrier to operatively connect the carriers to the shaft or disconnect them therefrom; a shifter for each clutch; and a latch coöperating with said shifters to normally maintain one of the clutches in operative engagement to connect one of the carriers to the driving shaft and the other clutch in inoperative position; a pair of trippers to actuate the latch to release either one of said clutches to operatively connect its coöperating record carrier to the shaft; and a rotatable drum having adjustable pins to coöperate with the trippers at predetermined times to actuate the trippers.

8. In a sound reproducing apparatus, the combination of a pair of record carriers; a

- 6
- shaft to drive both of said carriers; a clutch for each carrier to operatively connect the carriers to the shaft or disconnect them therefrom; a shifter for each clutch; a latch 5 coöperating with said shifters to normally maintain one of the clutches out of operative engagement and permit the other to engage to connect one of the carriers to the shaft; a pair of trippers to actuate the latch to release either one of said clutches to operatively connect its coöperating carrier to the shaft; and means to actuate the trippers at a predetermined time.
9. In a sound reproducing apparatus, the combination of a pair of record carriers; a shaft to drive both of said carriers; a clutch for each carrier to operatively connect the carriers to the shaft or disconnect them therefrom; a shifter for each clutch; a latch 10 coöperating with said shifters to normally maintain one of the clutches out of operative engagement and permit the other to engage to connect one of the carriers to the shaft; a pair of trippers to actuate the latch to release either one of said clutches to operatively connect its coöperating carrier to the shaft; and means to actuate the trippers at a predetermined time.
- 15 10. In a sound reproducing apparatus, the combination of a pair of record carriers; a shaft to drive both of said carriers; a clutch for each carrier to operatively connect the carriers to the shaft or disconnect them therefrom; a shifter for each clutch; a latch 20 coöperating with said shifters to normally maintain one of the clutches out of operative engagement and permit the other to engage to connect one of the carriers to the shaft; a pair of trippers to actuate the latch to release either one of said clutches to operatively connect its coöperating carrier to the shaft; and means to actuate the trippers at a predetermined time, comprising a pair of rockers, a pair of pivoted trip arms to rock said rockers, and a rotatable drum having laterally projecting pins to engage with and trip the arms.
- 25 11. In a sound reproducing apparatus, the combination of a pair of record carriers; a shaft to drive both of said carriers; a clutch for each carrier to operatively connect the carriers to the shaft or disconnect them therefrom; a shifter for each clutch; a latch 30 coöperating with said shifters to normally maintain one of the clutches out of operative engagement and permit the other to engage to connect one of the carriers to the shaft; a pair of trippers to actuate the latch to release either one of said clutches to operatively connect its coöperating carrier to the shaft; and means to actuate the trippers at a predetermined time, comprising a pair of rockers extending across the machine, a pair of pivoted trip arms supported to have movement transversely of the machine in a direction parallel with the rockers, a rotatable drum having a spiral groove in which a portion of the arm support engages, and pins projecting laterally from the drum to actuate the arms.
- 35 12. In a sound reproducing apparatus, the combination of a pair of record carriers; a shaft to drive both of said carriers; a clutch for each carrier to operatively connect the carriers to the shaft or disconnect them therefrom; a shifter for each clutch; a latch 40 coöperating with said shifter to normally maintain one of the clutches out of operative engagement and permit the other to engage to connect one of the carriers to the shaft; a pair of trippers to actuate the latch to release either one of said clutches to operatively connect its coöperating carrier to the shaft; and means to actuate the trippers at a predetermined time, comprising a pair of rockers extending across the machine, a pair of arms supported to have movement transversely of the machine in a direction parallel with the arms, one of said arms having a forked portion and the other arm a portion projecting in a plane between the forks of the projection of the other arm, spring influenced pawls carried by the arms adapted to rock the rockers when the arms are moved in one direction, a rotatable drum having a spiral groove in the periphery, a spring detent carried by the arm support to releasably engage in said groove to cause the arms to move transversely and to permit the release of said support to move the arms in a reverse direction, and a series of pins carried by the drum to engage with the arm projections, substantially as and for the purpose specified.
- 45 13. In a sound reproducing apparatus, the combination of a pair of record carriers; a driving shaft to drive said carriers; a normally disconnected clutch for said carrier; means including a rotatable drum having laterally projecting pins to cause either one of said clutches to operatively connect its coöperating carrier to the shaft at a pre- 50
